CLAIM

The ornamental design for a push-to-talk communication device having raised buttons, as shown and described.

(21) Appl. No.: **29/435,065**

DESCRIPTION

(22) Filed: **Oct. 19, 2012**

FIG. 1 is a front perspective view showing my new design for a push-to-talk communication device having raised buttons.

(30) **Foreign Application Priority Data**

FIG. 2 is a front view thereof;

Apr. 27, 2012 (EM) 1324016

FIG. 3 is a rear view thereof;

(51) **LOC (10) Cl.** **14-01**

FIG. 4 is a left side view thereof;

(52) **U.S. Cl.**

FIG. 5 is a right side view thereof;

USPC **D14/225**; D14/137

FIG. 6 is a top view thereof; and,

(58) **Field of Classification Search**

FIG. 7 is a bottom view thereof.

USPC D14/137, 205–206, 223, 224, 225, 226,
D14/227, 228, 229; 381/90, 91, 122, 16,
381/361, 357; 181/242, 355; 174/653

The broken lines depict unclaimed portions of the push-to-talk communication device having raised buttons, which form no part of the claimed design.

See application file for complete search history.
